(57) CLAIM

The ornamental design for an indoor cultivation apparatus as shown and described.

DESCRIPTION

The patent or application file contains at least one drawing executed in color. Copies of this patent or patent application publication with color drawing(s) will be provided by the Office upon request and payment of the necessary fee.

1. Indoor cultivation apparatus

1.1: Front

1.2: Back

1.3: Right

1.4: Top

1.5: Bottom

1.6: Front, top, right perspective

1.7: Cross-sectional

1.7 is a cross-sectional view sectioned vertically at the center of the front view and shown in perspective. The left side view is omitted because it is a mirror image of the right side view.

The broken lines and lighted portions within the broken lines illustrate portions of the indoor cultivation apparatus that forms no part of the claimed design.
